UNITED STATES PATENT OFFICE

135,347

DESIGN FOR A COMBINED SOLE AND HEEL OF A SHOE

Harold L. Pierson, Rochester, N. Y., assignor to
E. P. Reed & Co., Rochester, N. Y., a corpora-
tion of New York

Application August 6, 1942, Serial No. 107,830

Term of patent 7 years

To all whom it may concern:

Be it known that I, Harold L. Pierson, a citizen of the United States of America, residing at Rochester, in the county of Monroe and State of New York, have invented a new, original, and ornamental Design for a Combined Sole and Heel of a Shoe, of which the following is a specification, reference being had to the accompanying drawing, forming a part thereof.

In the drawing:

Fig. 1 is a plan view of a combined sole and heel of a shoe showing my new design, and

Fig. 2 is a longitudinal sectional view of the same as it appears when the sole is slightly flexed.

The characteristic features of my design for

a combined sole and heel of a shoe, substantially as shown, reside in a shoe sole having a multiplicity of narrow grooves or spaces extending transversely of the ball and arch portions, the grooves or spaces between the toe and ball portion being straight and extending at right angles to the longitudinal axis of the shoe sole, while the grooves or spaces at the rear of the ball portion and across the arch portion to the heel are of varying curvature and extend generally in a direction inclined to that of the grooves or spaces at the forward part of the sole.

I claim:

The ornamental design for a combined sole and heel of a shoe, as shown.

HAROLD L. PIERSON.
